T. B. WHITE, OF NEW BRIGHTON, PENNSYLVANIA.

Letters Patent No. 87,741, dated March 9, 1869; antedated February 27, 1869.

IMPROVED IRON BRIDGE.

The Schedule referred to in these Letters Patent and making part of the same.

To all whom it may concern:

Be it known that I, T. B. WHITE, of New Brighton, in the county of Beaver, and State of Pennsylvania, have invented certain new and useful Improvements in the Construction of Iron Bridges; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in a novel manner of constructing iron beams for braces, and similar purposes, in building bridges and similar structures, and also in forming a combined tie-bar and angle-iron, or step, for braces, of wrought-iron or steel, in one piece, as hereinafter explained.

Figure 1 is a side elevation of a beam constructed on my plan;

Figure 2 is an end view of the same;

Figure 3 is the same slightly modified;

Figure 4 is a face or plan view of my combined tie-bar and brace-step; and

Figure 5 is an end view of the same.

Figures 6, 7, and 8, represent portions of a bridge, with these improved parts in place, as they are intended to be used.

In constructing bridges and similar structures of iron, and in all cases where iron girders, beams, or braces are used, it is an object to combine the greatest possible amount of strength with the least possible weight, and for this purpose many forms of both solid and tubular bars have been designed. In braces, the element of rigidity is also important, and it is for this use mainly that my present form of beam is designed.

To construct my improved beam, I first form a series of bars, curved transversely, as represented by *a*, figs. 2 and 3, by rolling them in that shape. I then take four of these bars, after having made holes for rivets along their edges, and place their convex sides inward, and unite them firmly by rivets, as shown in figs. 1, 2, and 3. By this means I form a beam that is tubular and light, and which is provided with four radial flanges, which greatly stiffen it, and tend to prevent flexure, when used as a brace, and which, at the same time, form convenient and salient points for bolting or otherwise attaching other bars or pieces to them.

When these beams are to be used as chords, or girders, I construct them with a central flat bar, bolted or riveted vertically between the bars *a*, as represented by *b* in fig. 3.

In constructing iron, and even wooden bridges, it is customary to use cast-iron angle-blocks, to receive and hold the ends of the braces and bolts.

Experience has shown that these blocks are exceedingly liable to crack or break, especially at the point

where holes are made to receive the bolts that pass through them.

When these cast-iron blocks are used in building iron bridges, having two or more chords, or girders, side by side, it is customary to unite or tie the girders together, by means of separate wrought-iron bars, bolted transversely across them.

To form a safer, lighter, and stronger article, which shall answer the combined purpose of tie-bar and angle-block for the braces, I construct a wrought-iron plate, as represented by *B*, figs. 4 and 5. This bar may be made of any desired length, and with a horizontal flange, *c*, on each side, to bolt it fast to the beams or girders, and its central portion raised in a V-form, as shown in fig. 5, the faces *d* of the raised portion standing at an angle, to correspond with the angle at which it is intended to place the braces, the latter being indicated by dotted lines in fig. 5, and being shown in side elevation, with the plates *B*, in position, both at top and bottom, in fig. 7; fig. 8 being a front view of three braces, similarly arranged, the two outside ones being inclined in one direction, and the central one, in the opposite direction.

Fig. 6 is a plan view of a bridge-bed, or frame, consisting of a series of three girders, or chords, on each side, and showing the improved tie-bar and brace-block, applied, by being bolted thereon, ready to receive the braces.

In case the structure is very heavy or large, the bar *B* may be stiffened, or supported transversely, where the braces are to rest upon it, by forming it with cross-bars *n*, as shown in fig. 5; and, if desired, a projecting piece, or lug *o*, may be formed thereon, and made to fit between the girders *A*, or to be bolted to the sides thereof.

It is obvious that this plate is equally well adapted to wooden truss-bridges as to iron.

I would here remark that these beams *A* and bars *B* are more especially intended for use in connection with the improved iron beam recently invented by me, and on which I have already made application for a patent.

Having thus described my invention,

What I claim, is—

1. The wrought-iron beam, or brace, consisting of the segmental or curved plates *a* united, with their convex sides inward, with the cross-plate *b*, secured at their edges by rivets, substantially as shown and described.

2. The wrought-iron brace-block and tie-bar combined, when constructed substantially as herein described.

T. B. WHITE.
